N. S. BARTON, OF MANNSVILLE, NEW YORK.

Letters Patent No. 94,381, dated August 31, 1869.

IMPROVEMENT IN CHURNS.

The Schedule referred to in these Letters Patent and making part of the same.

To all whom it may concern:

Be it known that I, N. S. BARTON, of Mannsville, in the county of Jefferson, and State of New York, have invented certain new and useful Improvements in Churns; and I do hereby declare that the following is a full, clear, and exact description of the same, reference being had to the accompanying drawing, and to the letters of reference marked thereon, making part of this specification, in which—

Figure 1 is a top plan view of the dashers, showing the relative position of the gearing.

Figure 2 is an end view, the outer face of the driving-wheel being removed, so as to more clearly illustrate the operating-mechanism.

Figure 3 is a plan view of the centre dasher.

Figure 4 is a plan view of one of the side dashers.

The nature of my invention consists in passing horizontally, through openings in the ends of a suitable churn-box, a shaft, to which is permanently secured a centre dasher, composed of two flat parallel tapering arms, connected by a short tube.

Around this shaft, and between the centre dasher and the sides of the box, are two side dashers, which are also secured to a tube, the diameter of this tube being such as to allow of its free revolution around the centre shaft.

These side dashers are composed of a straight arm and double reversed L-arms.

The centre and side dashers are so connected with the shaft and side gearing, that when the churn is in operation, a reverse motion is imparted to the same.

Owing to the diameter of the driving-wheel being so much greater than that of the intermediate gear-wheels, it will readily be observed, that with but little power, an immense rate of speed can easily be obtained.

In order to lessen, in a still greater degree, the labor of churning, I propose to form the main driving-wheel of iron, and have it cast very heavy, so that it will perform the double office of driving and balance-wheel.

This churn has been practically tested, and experience has fully attested the fact, that owing to the system of dashers employed, the immense velocity with which they are driven, and the fact that they travel circuits running in opposite directions, enables me not only to successfully churn milk, but also to produce butter in one-fourth the time ordinarily required.

The great advantage of giving to the dashers the movement stated, is that the reverse currents are thus brought together with such force that the globules will be dashed in opposite directions, and thoroughly broken, thus rendering the task of separating the fat and oily part of the milk from the curdy one of but little labor, and, at the same time, accomplishing it in the shortest space of time.

To enable others skilled in the art to make and use my invention, I will now proceed to describe its construction and operation.

A is the churn-box or body, which may be of any desired form. I prefer the circular, and constructed of either wood or metal.

This box A rests on suitable legs or other supports A¹ A¹, and is provided with a hinged top, A².

a a are openings in the ends A³ A³ of the box.

Through these openings a a pass the tube-necks b, which are connected with the pinions B B, working on the outside of the box.

Through these tube-necks b b and the opening in the centre of the pinion-wheel B passes a shaft, C.

The diameter of this shaft C is such as to allow of its free revolution in the necks B B without imparting motion to the same.

D is the centre dasher, and is firmly secured to the shaft C, so as to revolve with it.

The form of this dasher D is clearly shown in fig. 3, and consists of two flat tapering arms d d, connected by a short tube, d'.

These arms d d are of such width at their point of connection with the tube d' as to allow of suitable openings being cut in the former, for the reception of the ends of the latter.

The faces of these arms d d may be slightly scooped, which affords a better cutting-surface.

E E are two side dashers, and are permanently secured to the tube-necks b b, having openings in their centre, which pass over said necks.

These dashers are partly constructed on the same principle as the dasher D, being composed of straight arms e e¹, parallel with each other, and connected by a tube, e²; but the distance between the arms e e¹ is not so great as that between the arms d d of the dasher D, and, besides, the inner arm e¹ is connected with an L-shaped arm, e³. The form of this dasher is clearly shown in fig. 4.

When the churn is in motion, the arms d d pass freely through the spaces x x, left open between the arms e¹ and e³.

The horizontal shaft C is circular in form, except at its ends, where it should be square or hexagonal, to allow of its secure attachment to the main driving-wheel F.

This wheel F is made of iron, and is cast heavy, so as to serve as a balance as well as a driving-wheel. It is also provided with a flange, F', around the inner surface of which are a series of teeth, f.

g g are shoulders or stumps, projecting from the ends of the box, and around which revolve gear-wheels G G.

This entire system of gearing is clearly shown in fig. 2.

The operation is as follows:

Motion is given to the wheels F F by means of a crank-handle, *f*, or other device. (There may be a handle on each wheel, if desired, so that two can work the churn at the same time.) This movement of the wheels F F causes the shaft C to revolve, which carries with it the dasher D, causing it to travel in the same direction as the wheels. This revolution of the wheels also imparts motion to the gear-wheels G G, which, in turn, impart motion to the pinion-wheels B B, and thus revolve, in an opposite direction from the wheels F F, the necks B B' and dashers E E.

Having thus fully described my invention, What I claim therein as new, and desire to secure by Letters Patent of the United States, is—

1. The driving-wheels F F, gear-wheels G G, pinion-wheels B B, and shaft C, when the same are so com-

bined and arranged that a double reverse motion is obtained by the revolution of the wheels F F, so that dashers that are attached to the shaft are caused to travel in opposite directions, substantially as described.

2. The dashers D and E, when the former is permanently connected to the shaft C, and the latter to the tube-neck *b*, and both in such manner, that through the wheels B F G, they are caused to travel and work in opposite circuits, substantially as described.

In testimony whereof, I have signed my name to this specification, in the presence of two subscribing witnesses.

N. S. BARTON.
